UNITED STATES PATENT OFFICE.

WARREN K. WILLIAMS, OF CUYAHOGA FALLS, OHIO, ASSIGNOR TO THE VAUGHN MACHINERY COMPANY, OF CUYAHOGA FALLS, OHIO, A CORPORATION OF OHIO.

WIRE-DRAWING DRUM.

Application filed July 22, 1925. Serial No. 45,239.

To all whom it may concern:

Be it known that I, WARREN K. WILLIAMS, a citizen of the United States, and a resident of Cuyahoga Falls, county of Summit, and 5 State of Ohio, have invented a new and useful Improvement in Wire-Drawing Drums, of which the following is a specification, the principle of the invention being herein explained and the best mode in which I have 10 contemplated applying that principle, so as to distinguish it from other inventions.

The present improvements relate more particularly to a take-up attachment for the gripper of a horizontal type of drawing block, e. g. a bull block such as is employed 15 in drawing the heavier gauges of wire or rod. In the operation of such a drawing drum or block, even more perhaps than in the case of a vertically disposed block, while the rod initially holds the gripping device and 20 chain or equivalent linked member whereby it is attached to the block against the surface of the latter, as the coils of rod build up, the first turns are forced out from the inner larger ring of the drum and correspondingly loosen up. As a result, unless the 25 gripping device and links are in some manner held in they will fly out from the revolving block and thus constitute a menace to the 30 operator.

The object of the present invention is to overcome this condition by providing means 35 for holding the gripper at all times closely against the block. The device is so constructed as to be capable both of automatic and manual operation, and while particularly described as designed for use on a horizontal block it will be understood that it 40 may be adapted for use on the other types of blocks or drawing drums.

To the accomplishment of the foregoing and related ends, said invention, then, consists of the means hereinafter fully described and particularly pointed out in the claims, 45 the annexed drawing and the following description setting forth in detail certain mechanism embodying the invention, such disclosed means constituting, however but one of various mechanical forms in which 50 the principle of the invention may be used.

In said annexed drawing:-

Fig. 1 is a front elevational view of a horizontal drawing block equipped with my present improved take-up mechanism; and 55 Fig. 2 is partly a side elevation and partly a

central section of such block and device, the plane of the section being indicated by the line 2—2, Fig. 1.

The horizontal drum 1 illustrated in the several figures of the drawing is of familiar construction, being mounted on the projecting end of a shaft 2 as usual, such drum, it will be noted, has a tapering surface, about which the wire or rod is coiled, and at its inner larger end it is provided with a flange 3, against which the coils are initially formed, being then gradually forced outwardly, i. e. toward the right in Fig. 2. A plurality of circumferentially spaced pins 4 project from the front face of the drum and are adapted to receive such coils as they are forced entirely off the drum proper.

The gripper 5, whereby the end of the wire or rod is seized preparatory to beginning of the drawing operation, is attached to the drum through the medium of a flexible member 6 consisting, as shown, of a plurality of links on the order of a chain, and a portion of the lateral face of the drum is cut away to provide a recess 7 in which such gripper and links are received when the gripper is pulled in by the drawing operation, this position of the parts being shown in dotted outline in Fig. 1, while the full line position thereof is that occupied when the end of the rod or wire is to be seized by the gripper 5.

As previously explained, the device of present interest consists of means provided for holding the parts in question thus 90 against the drum, despite the action of centrifugal force which tends to throw them outwardly as the coils become loosened.

The special means thus provided include a spindle 10 rotatably mounted in the drum 1 co-axially therewith, such spindle being journaled at an intermediate point in an apertured boss 11 projecting from a plate 12 that closes the front face of the drum and also having its inner end stepped in a recess 13 in the end of spindle 2, that forms a bearing therefor. Keyed or otherwise non-rotatably secured to the portion of the spindle 10 that lies within the drum is a supplemental smaller drum 14, to which is attached one end of a flexible cable 16, the other end of which is attached to gripper 5. Also keyed to said spindle, and lying adjacent the outer face of drum 14, is a ratchet wheel 17, while similarly non-rotatably 105

mounted on the outer end of the spindle beyond boss 11 is a hand wheel 18. A pawl 19 is pivotally secured to plate 12 in operative relation to said ratchet wheel 17, the pin 20, 5 that carries said pawl, projecting through the plate and having secured to its outer end a handle 21 whereby the pawl may be actuated to release the ratchet wheel, a spring 22 normally pressing such pawl into engagement with the wheel. One side of the hand wheel is enlarged to provide a weight 23, which tends to hold said wheel in the position shown, i. e. to prevent rotation of the spindle 10 and the attached drum 14 and 10 ratchet wheel 17 even though the winding drum or block 1 is rotating.

The operation of the take-up attachment just described may now be briefly set forth. The direction of rotation of the drawing block being as shown by the arrow in Fig. 20 1, it is evident that as the gripper 5, after being initially pulled in by the wire or rod that is being drawn, will travel around with the block. The supplemental drum 14, however, tends to remain stationary under the influence of weight 23, i. e. does not at first 25 take up the rotation of the block, and as a result the cable 16 will be automatically wound up on said supplemental drum, and 30 when thus wound up will be so held by the action of the spring-pressed pawl 19. Accordingly, the gripper 5 and link 6 cannot by any possibility fly out, no matter how 35 loose the coils of wire on the drum may become. If desired the operator can of course turn the hand wheel 18 backwards, i. e. opposite to the direction of rotation of the drawing block, and in that manner quickly 40 tighten up the cable without waiting for this to be done automatically. When it is desired to draw the gripper out into position for seizing the end of a fresh rod the pawl is released through the medium of operating handle 21 and the hand wheel 18 then 45 rotated to unwind cable 16, or such cable will of course be unwound by simply pulling outwardly on the gripper.

Other modes of applying the principle of my invention may be employed instead of the one explained, change being made as regards the mechanism herein disclosed, provided the means stated by any of the following claims or the equivalent of such stated 50 means be employed.

I therefore particularly point out and distinctly claim as my invention:—

1. In mechanism of the character described, the combination of a rotatable drawing drum, a gripper, a flexible member connecting the latter with said drum, and means adapted to hold said gripper to said drum against centrifugal force, said means including a supplemental drum mounted on 60 said drawing drum, a cable connecting said gripper to said supplemental drum, and

means adapted to rotate the latter independently of said drawing drum.

2. In mechanism of the character described, the combination of a rotatable drawing drum, a gripper, a flexible member connecting the latter with said drum, and means adapted to hold said gripper to said drum against centrifugal force, said means including a supplemental drum mounted on 70 said drawing drum, a cable connecting said gripper to said supplemental drum, and means adapted automatically to rotate the latter independently of said drawing drum.

3. In mechanism of the character described, the combination of a rotatable drawing drum, a gripper, a flexible member connecting the latter with said drum, and means adapted to hold said gripper to said drum against centrifugal force, said means including a supplemental drum mounted on 80 said drawing drum, a cable connecting said gripper to said supplemental drum, means adapted to rotate the latter independently of said drawing drum, and means normally limiting rotation of said supplemental drum to one direction.

4. In mechanism of the character described, the combination of a rotatable drawing drum, a gripper, a flexible member connecting the latter with said drum, and means adapted to hold said gripper to said drum against centrifugal force, said means including a supplemental drum mounted on 90 said drawing drum, a cable connecting said gripper to said supplemental drum, means adapted automatically to rotate the latter independently of said drawing drum, and means normally limiting rotation of said supplemental drum to one direction.

5. In mechanism of the character described, the combination of a horizontal drawing drum, links flexibly connecting the latter with said drum, and means adapted to hold said gripper to said drum against centrifugal force, said means including a supplemental drum rotatably mounted on 100 said drawing drum co-axially therewith, a cable connecting said gripper to said supplemental drum, and a weight connected with said supplemental drum and tending 110 to hold the same against rotation with said drawing drum.

6. In mechanism of the character described, the combination of a horizontal drawing drum, links flexibly connecting the latter with said drum, and means adapted to hold said gripper to said drum against centrifugal force, said means including a supplemental drum rotatably mounted on 120 said drawing drum co-axially therewith, a cable connecting said gripper to said supplemental drum, a weight connected with said supplemental drum and tending to hold the same against rotation with said drawing drum, and pawl and ratchet means 125

normally limiting rotation of said supplemental drum to one direction.

7. In mechanism of the character described, the combination of a horizontal drawing drum, links flexibly connecting the latter with said drum, and means adapted to hold said gripper to said drum against centrifugal force, said means including a spindle rotatably mounted in said drum ¹⁵
5 axially therewith, a supplemental drum 10 lying within said drawing drum and fixed

to said spindle, a weighted hand-wheel lying without the forward face of said drawing drum and likewise fixed to said spindle, a ratchet wheel on the latter, and a releasable pawl for said ratchet wheel carried by said drawing drum, whereby rotation of said supplemental drum may be limited to a predetermined direction.

Signed by me this 18 day of July, 1925.

WARREN K. WILLIAMS.
